UNITED STATES PATENT OFFICE

SAUL EMMANUEL MELKMAN, OF MONTREAL, QUEBEC, CANADA

HAIR WAVING DEVICE

Application filed February 26, 1930, Serial No. 431,509, and in Canada February 27, 1929.

The present invention relates to improvements in hair waving devices especially of the type employed for forming lasting Marcel waves.

5 An important object of the invention is the provision of a hair waving device which will form the curls and waves quickly and in a lasting manner.

10 A further object of the invention is the provision of a hair waving device having a mandrel disposed for partial circumferential movement to impart an ironing or calendering effect to the hair.

15 Another object of the invention is the provision of a hair waving device having a mandrel mounted for oscillating movement.

20 Still another object of the invention is the provision of a hair waving device embodying a mandrel mounted for partial circumferential oscillating movement and means for operating the mandrel to effectively press the hair.

25 Other objects and advantages of the invention will become apparent as the description progresses.

30 In the accompanying drawings forming a part of this specification and in which like reference characters are employed to designate corresponding parts throughout the same:—

Figure 1 is a perspective view of the assembled waving device;

Figure 2 is a longitudinal sectional view through the same;

35 Figure 3 is a transverse section taken on the line 3—3 of Figure 2, in one position;

Figure 4 is a similar view showing the mechanism in opposed position, and

40 Figure 5 is an enlarged transverse section taken on the line 5—5 of Figure 2.

Referring to the drawings, wherein for the purpose of illustration is shown a preferred embodiment of the invention, the numeral 10 generally designates a transversely elongated casing formed in the upper portion of its front wall with an opening and in the lower portion of its rear wall with a rearwardly directed annular flange 11. The upper portion of the casing 10 supports a mandrel 12 embodying an exterior metallic shell

13 of elongated tubular form carrying at its interior an electric heating element 14. One end of the mandrel is disposed in the upper portion of the casing 10 and is journaled for partial circumferential movement there- 55 in.

A rearwardly extending casing extension 15 is attached to the flange 11 and is formed at its rearward extremity with a comparatively flat, transversely elongated gear housing 60 16. An extension section 17 extends rearwardly from the lower portion of the housing 16 and forms a conduit for a power-operated drive shaft 18.

65 Journaled within the casing extension 15, so that one end projects within the lower portion of the casing 10 while the opposed or rear end extends within the housing 16, is a transmission shaft 19. The forward end of this shaft actuates a spur gear 20 fixed thereon and operates within the lower portion of the casing 10. The gear 20 is disposed immediately below and is in mesh with a complementary spur gear 21 fixed on the inner portion of the mandrel 12. 70 75

70 The rear end of the transmission shaft 19 carries a crank 22 rigidly fixed on the shaft and provided with a depending arm 23 in the outer extremity of which is mounted a rearwardly extending pin 24. 80

85 On the forward extremity of the drive shaft 18 is fixed a crank actuating cam 25 embodying a flat annular plate rigidly secured to the drive shaft and formed at its forward face with an annular eccentric groove 26. Thus, the crank pin 24 is mounted to engage the cam groove 26 so that the crank 22 will be oscillated upon rotary operation of the cam 25.

90 The heating element 14 of the mandrel is electrically connected with a source of electrical supply through the medium of conductors 27 which enter the mandrel shell 13 through a tubular bearing extension 28.

95 Pivotedly connected with the casing 10, for selective adjustment, is a clamping member 29 embodying an intermediate offset bracket portion pivoted to the casing and a forwardly projecting clamping jaw 30. The jaw 30 is bent to assume an arcuate form in cross 100

section designed to conform to the exterior contour of the mandrel shell and to clamp the hair on the mandrel over practically the entire length thereof. The opposed end of the 5 clamping member is formed with a rearwardly extending operating handle 31 disposed for convenient adjustment by the operator.

In use, the strands of hair are initially arranged flat upon the mandrel 12 and are firmly clamped thereon by adjustment of the 10 clamping jaw 30. The electric heating element is energized and the driving connection properly effected so that the mandrel will be actuated in a partial rotary movement or 15 rather circumferentially oscillated. This movement of the mandrel simultaneously with the heating, will produce an ironing or calendering effect to the hair so that the 20 Mandrel waves will be rapidly formed in a lasting manner.

It is to be understood that the form of my invention herein shown and described is to be taken as a preferred example of the same, and that various changes as to the shape, size, 25 and arrangement of parts may be resorted to without departing from the spirit of the invention or the scope of the subjoined claims.

Having described my invention, I declare that what I claim and desire to secure by Letters Patent is:—

1. A hair waving device comprising a casing, a hollow mandrel having one end journaled in the casing, a clamping member operable to clamp the hair on the mandrel, 35 means within the mandrel for heating it, and mechanism for circumferentially oscillating the said mandrel independently of the clamping member.

2. In a hair waving device, a casing, a 40 mandrel having one end projecting in the casing and journaled therein, a clamping member operable to firmly clamp the hair on the mandrel, a power-operated rotary drive shaft, and mechanism operatively connected 45 with the rotary drive shaft and with the mandrel adapted to convert the rotary motion of the drive shaft to a circumferential oscillating movement of the mandrel.

3. In a hair waving device, a casing, a 50 hollow mandrel having one end journaled in the casing, a clamping member operable to clamp the hair on the mandrel, electric heating means disposed in the mandrel, a rotary drive shaft, and actuating means operatively connected 55 with the drive shaft and with the mandrel adapted to impart a circumferential oscillating movement to the mandrel upon rotary operation of the drive shaft.

4. In a hair waving device, a casing, a 60 hollow mandrel having one end journaled in the casing, a clamping member pivotally connected with the casing operable to clamp the hair on the mandrel, electric heating means within the mandrel, a transmission shaft 65 journaled in the casing, and intergeared with

the mandrel, a second housing rigidly attached to the first one, a rotary drive shaft journaled in this second housing, and means within said housing operatively connecting the drive shaft and the transmission shaft 70 adapted to convert the rotary motion of the former to an oscillatory motion of the latter.

In witness whereof I have affixed my signature hereto.

SAUL EMMANUEL MELKMAN.
